TIRE

Samuel Charles Parker, Erdington, Birmingham, England, assignor to Dunlop Tire and Rubber Corporation, Buffalo, N. Y., a corporation of New York

Application April 17, 1951, Serial No. 14,876
In Great Britain November 8, 1950

Term of patent 14 years

(Cl. D90—20)

To all whom it may concern:

Be it known that I, Samuel Charles Parker, a subject of the King of Great Britain, residing at 67 Woodlands Farm Road, Erdington, Birmingham, England, have invented a new, original, and ornamental Design for a Tire, of which the following is a specification, reference being had to the accompanying drawing, forming a part hereof.

Fig. 1 is a perspective view; and

Fig. 2 is a plan view of a section of a tire showing my new design.

I claim:

The ornamental design for a tire, as shown.
SAMUEL CHARLES PARKER.
